[57] **CLAIM**

The ornamental design for a bedstead, as shown and described.

DESCRIPTION

FIG. 1 is a top plan view of a bedstead showing my new design;

FIG. 2 is a front elevational view thereof, the rear being similar in appearance;

FIG. 3 is a right end elevational view thereof, the left end being a mirror image thereof;

FIG. 4 is a perspective view thereof from the top, front and right end; and,

FIG. 5 is a vertical cross-sectional view thereof on line 5—5 of FIG. 1.
